(57) **CLAIM**

The ornamental design for an electrical charger, as shown and described.

DESCRIPTION

FIG. 1 is a front perspective view of the electrical charger; FIG. 2 is a front elevational view of the electrical charger; FIG. 3 is a left side elevational view of the electrical charger; FIG. 4 is a right side elevational view of the electrical charger;

FIG. 5 is a top plan view of the electrical charger;

FIG. 6 is a bottom plan view of the electrical charger;

FIG. 7 is a rear elevational view of the electrical charger; and,

FIG. 8 is another front perspective view of the electrical charger showing it affixed to an unclaimed mounting board that can be attached to a wall.

The dashed lines are for the purpose of illustrating portions of the electrical charger that form no part of the claimed design. Dashed lines directly adjacent to shaded areas represent the boundaries of the claimed design and form no part thereof.

1 Claim, 6 Drawing Sheets
